(57) **CLAIM**

The ornamental design of a multi-compartment insulative carrying case, as shown and described.

DESCRIPTION

FIG. 1 is a perspective view of a multi-compartment insulative carrying case showing our new design;

FIG. 2 is a top plan view thereof;

FIG. 3 is a front view thereof;

FIG. 4 is a side view thereof, the opposite side being identical thereto;

FIG. 5 is a rear view thereof; and,

FIG. 6 is a bottom plan view thereof.

The broken lines are for illustrative purposes only and form no part of the claimed design.
